HEAT RESPONSIVE SWITCHES
Earnest F. Swanson, R.R. 1, Bristol, Ind.
Filed May 5, 1960, Ser. No. 27,103
8 Claims. (Cl. 200—138)

This invention relates to improvement in heat responsive switches. The principal objects of this invention are:

First, to provide a heat responsive switch which will be simple and inexpensive to manufacture and assemble yet accurate and long lived in operation due to the protected position of its contacts.

Second, to provide a switch of the type described employing a heat expansible actuating element in which the calibration of the switch can be accomplished with a minimum of effort during assembly of the switch parts under various temperature conditions.

Third, to provide a switch of the type described which utilizes a minimum number of simple standardized parts which function as connecting terminals and also as openable and closable contacts in the switch assembly in some instances.

Fourth, to provide a type of switch structure which is readily adaptable to make and break a variety of circuits under different conditions of temperature variation.

Other objects and advantages of the invention will be apparent from a consideration of the following description and claims. The drawings, of which there is one sheet, illustrate one highly practical form of the switch and one modified form thereof.

FIG. 1 is a fragmentary side elevational view of the switch in one possible application thereof to sense the presence of a flame in an oil burner.

FIG. 2 is a cross sectional view taken along the plane of the line 2—2 in FIG. 1.

FIG. 3 is a cross sectional view taken along the plane of the angled line 3—3 in FIG. 2.

FIG. 4 is a fragmentary cross sectional view taken along the plane of the line 4—4 in FIG. 3.

FIG. 5 is a fragmentary cross sectional view similar to FIG. 3 but showing a modified arrangement of the switch parts.

The switch of the invention as illustrated is particularly adapted for use as a safety and regulating switch for oil burners but it has utility in other applications where a heat responsive switch is needed. FIG. 1 shows the nozzle 1 and supply pipe 2 of an oil burner. Starting terminals or spark points 3 are shown supported over the nozzle by a bracket 4 as is common. The switch of the invention enclosed in a metal case 5 is shown clamped to the pipe 2 by a bracket or clamp ring 6. Three electrical conductors or wires 7 extend from the switch to control the operation of the burner 1 and spark points 3 in a variety of different manners known to the art in response to temperature conditions in the case 5 as created by the burner 1.

Within the case 5 is a circular base 8 of heat resistant, electrically insulating material. The case 5 is sealed to the base 8 by a crimped rib 9 and flange 10 so the switch elements are protected from soot, dust and other foreign matter. Extending through the base 8 is a central terminal pin 11 and two terminal and contact pins 12 and 13 spaced radially from the center pin and

2

angularly from each other. It is a feature of the invention that the pins 11, 12 and 13 can be identical parts except that the inner ends of the pins 12 and 13 are desirably given a non-corrosive coating such as silver plate as at 14. The pins have outer ends 15 that are bored as at 16 to receive the ends of the wires 7 and be electrically connected thereto as by soldering. A flange 17 is embedded into the base and pins may be press fitted or molded into the base in the desired and designed positions to be described.

Pressed around the base of the center pin 11 and embedded into the inner face of the circular base 8 is an angled metal connector 18 having an upstanding flange 19. The connector 18 is thus electrically connected to the center pin 11 and coacts with a rotatable contact element 20. The contacting element 20 is a metal strip bent arcuately around the base of an insulating hub 21 rotatably mounted on the inner end of the central pin 11 (see FIG. 4). The contacting element 20 has radially projecting angularly spaced contact arms 22 and 23 which are desirably silver plated as at 24 where they contact the pins 12 and 13. A flexible electrical connector such as the coil 25 connects the contacting element 20 with the upstanding flange 19 of the connector bracket.

The upper end of the insulating hub 21 has parallel flattened sides 26 which are engaged by the sides of a U-shaped bend in the end of a spirally coiled driving spring 27. The outer end of the spring 27 is fixedly anchored at 28 to the upstanding arm of a bracket 29 secured to the base disk 8 at 30. The driving spring 27 is of the type which will expand and contract upon fluctuation in temperature and is desirably of bimetal construction. No attempt is made to illustrate bimetal as this is a well known expedient. The coiled driving spring 27 is located above the level of the pins 12 and 13 and is electrically insulated therefrom.

In operation of the switch the terminal pins 11, 12 and 13 are connected to the parts to be controlled. The central contacting element 20 and its arms 22 and 23 are electrically connected to the center pin 11 through the coil spring 25. Depending upon the temperature condition of the spiral driving spring 27 the contacting element 20 may be rotatably adjusted on the insulating hub 21 to position the contact arms 22 and 23 in the desired angular position relative to the pins 12 and 13. The case 5 can be then sealed to the base disk 8 and the switch assembly will thereafter function to make or break contacts between the pin 12 and contact arm 22 or the pin 13 and the contact arm 23 depending upon the expansion or contraction of the spiral driving spring 27. It is pointed out that any excess flexing of the driving spring 27 beyond that required to make the electrical contacts either in an expanding or contracting relation is readily accommodated by flexing of the contact arms 22 and 23. The silver plated surfaces 14 and 24 of the contacting elements prevent corrosion and sticking of the contacting surfaces so the switch will operate for long periods without attention. No difficult problems are encountered in the assembly and calibration of the switch assembly because as noted, the U-shaped end of the contacting element 20 has merely to be adjusted on the hub 21 to the desired angular position relative to the pins 12 and 13 corresponding to the temperature of the driving spring 27 at

the time of assembly. The switch will thereafter remain in calibration due to the tight gripping engagement of the U-shaped bend in the contacting element with the hub 21.

FIG. 5 illustrates a possible modified form of the switch assembly designed to make and break a third contact. The modified assembly includes a modified base disk 8A in which a fourth pin 13A is mounted in radially and angularly spaced relation to the pins 12 and 13 which are the same as in the first form of the switch. The same central mounting pin 11 is provided but the insulating hub 21A is arranged to receive a modified form of contacting element 20A having in addition to the angularly spaced arms 22 and 23 a third vertically and angularly spaced contacting arm 23A positioned to swing over the upper end of the pin 13 and into contact with the added terminal pin 13A. The pins 13 and 13A can be selectively positioned to make contact with their respective contact arms 23 and 23A in either the same or different rotated positions of the insulating hub 21.

It will thus be seen that a variety of circuits can be made and broken in response to temperature variations by the switch assembly of the invention.

The combination of elements in the switch believed to be patentably novel is set out in the following claims.

1. In a thermostatic switch assembly, a circular insulating base having a central terminal pin projecting therethrough and additional terminal pins projecting through said base in radially and angularly spaced relation to said central pin, an insulating hub rotatably mounted on the inner end of said central pin, a contacting element having a U-shaped bend adjustably and embracingly engaging said hub and having angularly spaced flexible contact arms projecting from the hub between said other terminal pins, means electrically connecting said contacting element with said central pin and permitting rotation of said hub, non-corrosive silver coatings on said contact arms and the coating portions of said other pins, a spiral thermally responsive driving spring having one end fixedly anchored relative to said base and having its other end drivingly engaged with said hub and positioned beyond the ends of said terminal pins, and a case enclosing said spring and hub and sealed to said base around the inner ends of said terminal pins.

2. In a thermostatic switch assembly, an insulating base having a central terminal pin projecting therethrough and additional terminal pins projecting through said base in radially and angularly spaced relation to said central pin, an insulating hub rotatably mounted on the inner end of said central pin, a contacting element having a U-shaped bend embracingly engaging said hub and having angularly spaced flexible contact arms projecting from the hub between said other terminal pins, means electrically connecting said contacting element with said central pin and permitting rotation of said hub, non-corrosive coatings on said contact arms and the coating portions of said other pins, a spiral thermally responsive driving spring having one end fixedly anchored relative to said base and having its other end drivingly engaged with said hub and positioned beyond the ends of said terminal pins, and a case enclosing said spring and hub and sealed to said base around the inner ends of said terminal pins.

3. In a thermostatic switch assembly, an insulating base having a first terminal pin projecting therethrough and additional terminal pins projecting through said base in radially and angularly spaced relation to said first pin, an insulating hub rotatably mounted on the inner end of said first pin, a contacting element having a U-shaped bend embracingly engaging said hub and having angularly spaced contacting arms projecting from the hub adjacent said other terminal pins, means electrically connecting said contacting element with said first pin and permitting rotation of said hub, non-corrosive coatings on said contact arms and the coating portions of said other pins, a spiral thermally responsive driving spring having one

end fixedly anchored relative to said base and having its other end drivingly engaged with said hub and positioned beyond the ends of said terminal pins, and a case enclosing said spring and hub and sealed to said base around the inner ends of said terminal pins.

4. In a thermostatic switch assembly, an insulating base having a first terminal pin projecting therethrough and an additional terminal pin projecting through said base in radially spaced relation to said first pin, an insulating hub rotatably mounted on the inner end of said first pin, a contacting element having a U-shaped bend embracingly engaging said hub and having a contacting arm projecting from the hub adjacent said other terminal pin, means electrically connecting said contacting element with said first pin and permitting rotation of said hub, non-corrosive coatings on said contact arm and the coating portion of said other pin, a spiral thermally responsive driving spring having one end fixedly anchored relative to said base and having its other end drivingly engaged with said hub and positioned beyond the ends of said terminal pins, and a case enclosing said spring and hub and sealed to said base around the inner ends of said terminal pins.

5. In a thermostatic switch assembly, an insulating base having a first terminal pin projecting therethrough and additional terminal pins projecting through said base in radially and angularly spaced relation to said first pin, an insulating hub rotatably mounted on the inner end of said first pin, a contacting element having a U-shaped bend adjustably and embracingly engaging said hub and having angularly spaced contacting arms projecting from the hub in rotatable contactable relation to said other terminal pins, means electrically connecting said contacting element with said first pin and permitting rotation of said hub, a spiral thermally responsive driving spring having a connection at one end to said hub and having its other end anchored to said base and positioned beyond the ends of said terminal pins, and a case enclosing said spring and hub and sealed to said base around the inner ends of said terminal pins.

6. In a thermostatic switch assembly, an insulating base having a first terminal pin projecting therethrough and additional terminal pins projecting through said base in radially and angularly spaced relation to said first pin, an insulating hub rotatably mounted on the inner end of said first pin, a contacting element having a first connection to said hub and having angularly spaced contacting arms projecting from the hub in rotatable contactable relation to said other terminal pins, means electrically connecting said contacting element with said first pin and permitting rotation of said hub, a spiral thermally responsive driving spring having a second connection at one end to said hub and having its other end anchored to said base and positioned beyond the ends of said terminal pins, one of said connections being angularly adjustable and a case enclosing said spring and hub and sealed to said base around the inner ends of said terminal pins.

7. A thermostatic switch comprising an insulating base, a plurality of terminal pins of like shape projecting through said base in spaced relation and adapted at their outer ends for connection to external electrical conductors, an insulating hub rotatably mounted on one of said pins on the inner end thereof, a contacting element having a driven supporting connection to said hub and having a flexible contact arm swingable therewith into contacting engagement with the side of another of said pins, a thermally responsive spiral driving spring anchored at one end relative to said base and having a rotary driving connection at its other end to said hub, one of said connections being angularly adjustable, means electrically connecting said contacting element to said one pin, and a case enclosing said spring and the inner ends of said pins and sealed to said base.

8. A thermostatic switch comprising an insulating base,

a plurality of terminal pins of like shape projecting through said base in spaced relation and adapted at their outer ends for connection to external electrical conductors, an insulating hub rotatably mounted on one of said pins on the inner end thereof, a contacting element having a driven supporting connection to said hub and having a contact arm swingable therewith into contacting engagement with another of said pins, a thermally responsive spiral driving spring anchored at one end relative to said base and having a rotary driving connection at its other end to said hub, one of said connections being angularly adjust-

able, means electrically connecting said contacting element to said one pin, and a case enclosing said spring and the inner ends of said pins and sealed to said base.
